(57) **CLAIM**

The ornamental design for a wireless earphone, as shown and described.

DESCRIPTION

FIG. 1 is a front and top perspective view of a wireless earphone according to a first embodiment of my new design; FIG. 2 is a back and bottom perspective view thereof; FIG. 3 is a front view thereof; FIG. 4 is a back view thereof; FIG. 5 is a left side view thereof; FIG. 6 is a right side view thereof; FIG. 7 is a top view thereof; FIG. 8 is a bottom view thereof;

FIG. 9 is a front and top perspective view of a wireless earphone according to a second embodiment of my new design;

FIG. 10 is a back and bottom perspective view thereof;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

The broken lines in the figures illustrate portions of the wireless earphone that form no part of the claimed design.

1 Claim, 16 Drawing Sheets
